(57) **CLAIM**

The ornamental design for a chute lockout device, as shown and described.

DESCRIPTION

FIG. 1 is a front perspective view of a chute lockout device, showing our new design, shown in a used condition with a mailbox and lock shown in broken lines;

FIG. 2 is another front perspective view thereof with the environmental structure removed for clarity;

FIG. 3 is rear perspective view thereof;

FIG. 4 is a front view thereof;

FIG. 5 is a rear view thereof;

FIG. 6 is a top view thereof;

FIG. 7 is a bottom view thereof;

FIG. 8 is a side view thereof; and,

FIG. 9 is an opposite side view thereof.

All features in broken lines are for the purpose of illustrating environmental structure and form no part of the claimed subject matter.

1 Claim, 5 Drawing Sheets
